(57) **CLAIM**

The ornamental design of the bracket, as shown and described.

DESCRIPTION

FIG. 1 is a top perspective view showing the top, front, and left sides of a bracket;

FIG. 2 is a bottom perspective view showing the rear, right, and bottom sides of the bracket;

FIG. 3 is a front elevation view of the bracket;

FIG. 4 is a rear elevation view of the bracket;

FIG. 5 is a left side elevation view of the bracket;

FIG. 6 is a right side elevation view of the bracket;

FIG. 7 is a top plan view of the bracket; and,

FIG. 8 is a bottom plan view of the bracket.

The broken line showing of a bracket is included for the purpose of illustrating environment as well as unclaimed portions of the bracket and forms no part of the claimed design.
